CLAIM

The ornamental design for a playhouse for displaying motion pictures, as shown and described.

DESCRIPTION

FIG. 1 is a front perspective view of a playhouse for displaying motion pictures showing my new design;

FIG. 2 is a front elevational view thereof;

FIG. 3 is a rear elevational view thereof;

FIG. 4 is a right side elevational view thereof; and

FIG. 5 is a left side elevational view thereof.

The bottom plan view of my new design is plain and unornamented.

FIG. 1

FIG. 2

FIG. 3

FIG. 4

FIG. 5
